UNITED STATES PATENT OFFICE.

IRVING H. ELLIOTT, OF NEW YORK, N. Y., ASSIGNOR TO HARRY E. CAMPBELL, OF MOUNT VERNON, NEW YORK.

METAL WINDOW-FRAME.

1,375,139.

Specification of Letters Patent. Patented Apr. 19, 1921.

Application filed July 1, 1919. Serial No. 307,945.

To all whom it may concern:

Be it known that I, IRVING H. ELLIOTT, a citizen of the United States, residing at New York, in the county of New York and 5 State of New York, have invented a certain new and useful Improvement in Metal Window-Frames, of which the following is a specification.

The invention relates to metal window-10 frames of the type set forth in U. S. Letters Patent No. 1,237,295 to Harry E. Campbell, dated August 21, 1917, wherein are comprised hollow jambs having their inner wall formed of three vertical sections, separated 15 by slots. The invention consists in an improvement of said jambs, whereby a portion of either of said slots may be varied in width without disturbing the remainder of the slot; whereby the width of said slots 20 may be initially adjusted, and whereby the construction of the jamb and especially of the inner wall thereof is simplified, cheapened and involves the use of less metal.

In the accompanying drawings—
25 Figure 1 is a vertical section of my window-frame. Fig. 2 is an elevation of a portion of said frame with parts broken away to show the supporting brackets for the inner jamb wall section D. Fig. 3 is a horizontal section on the line 3, 3 of Fig. 4. Fig. 4 is a vertical section, similar to Fig. 1, showing the sashes I, J in place in the frame. Fig. 5 is a vertical section on the line 5, 5 of Fig. 3.

30 Similar letters and numerals of reference indicate like parts.

The frame comprises the lintel A, the sill B and two hollow jambs C, alike in construction, one of which only is here shown.

40 The sill B, which is a casting resting upon the masonry of the window opening, has a flat portion 1 united to an outwardly and downwardly inclined portion 2 by a vertical portion 4. Near the outer edge of 45 the flat portion 1 is a groove 6. The top surface of the rib 7 formed between the groove 6 and the vertical portion 4 lies below the level of the flat portion 1, so that any water accumulating on said flat portion 50 1 and entering the groove 6 will flow over said rib 7, and so escape to the vertical and outwardly inclined portions of the sill. In this way, said sill is drained and water prevented from flowing into the building over 55 the rear edge of said flat surface.

The top wall 8, the rear wall 9 and the upper part of the front wall 10 of the lintel A are integrally formed of a bent metal plate. The lower part of wall 10 and a portion of the bottom wall of the lintel is 60 formed of a bent plate 11. The upper portion of plate 11 is united in any suitable way, as by welding, to wall 10. The rear edge of the horizontal portion of bent plate 11 is flanged upwardly and is inwardly inclined, as shown at 12. The remainder of the bottom wall of the lintel is formed of a plate 13 having its outer edge flanged upwardly and inwardly to face flange 12, as shown at 14. The inner edge of plate 70 13 is bent over to form a horizontal loop 15 which engages with a similar horizontal loop 16 on the lower edge of rear wall 9. The ends of the lintel are closed. In the 75 lintel bottom are openings which are covered by internal plates, one of which is shown at 17, secured in place by screws 18. The flanges 12, 14 extend upwardly between said plates into the lintel. Integral with each of said internal plates is a downwardly 80 projecting bar 19, Fig. 2. Directly beneath said bar and secured to the sill is a bracket 20. A plate D is attached to the outer faces of bar 19 and bracket 20 by means of screws 21 passing through horizontal slots. Said 85 plate, as will hereafter more fully be explained, forms one of the three sections which together form the inner wall of the jamb.

The two hollow jambs being, as heretofore stated, exactly alike, I proceed to describe the one shown in the drawings. (See Fig. 3.) A portion 24 of the front wall, the outer wall 25 and the rear wall 26 are formed integrally of a bent metal plate. 95 On the vertical edge of wall 26 is formed a loop 27 which engages with a similar loop 28 on the vertical edge of section D. 29 is a vertical channel plate, one arm of which is in line with section D and forms 100 another section E of the inner wall of the jamb. The opposite and parallel arm 30 is united to the bent over end 31 of front wall 24, so that the portion 32 of said channel plate 29 which connects section E and 105 arm 30 completes the front wall of the jamb. The arm 30 is wider than section E, so that between sections E and D there is a space, in which are disposed two narrow vertical plates F and G placed one above 110

the other, but separated at their abutting ends, as indicated at 33, Figs. 4 and 5. The top edge of plate F bears against the bottom of lintel A. The bottom edge of plate 5 G rests upon the flat upper surface of a shoulder 34 formed at one end of the inclined portion 2 of the sill B. The width of these plates F and G is the same, and is less than that of the space before referred to 10 as existing between the facing edges of sections E and D, so that two narrow slots 35, 36 are produced adjacent to said vertical plates F and G.

To the arm 30 of channel plate 29 are bolted four brackets, one of which is shown 15 at H; Fig. 3. The upper plate F is connected to the upper two of these brackets by screws 37, 38 passing through horizontal slots in said plate. In like manner, the 20 lower plate G is connected to the lower two of these brackets by screws 39, 40, also passing through horizontal slots in said plate. The two plates F and G thus supported register with sections D and E, so 25 that it will now be seen that the whole inner wall of the jamb consists of three sections, namely, D, E and the intermediate plates F and G disposed one above the other, between which sections, as I have stated, are 30 the two parallel vertical slots 35 and 36, extending from top to bottom of the wall.

This construction of the inner wall of the jamb simplifies and cheapens the manufacture of jambs of this general type, wherein 35 the inner wall is made of three vertical sections. Ordinarily the two outer sections of the three are secured to or form parts of the front and rear walls of the jamb and the middle section is supported by a vertical 40 plate extending across the interior of the jamb and secured to the opposite wall, such construction, for example, being shown in U. S. Letters Patent to Harry E. Campbell before noted. By the introduction of the 45 channel plate 29 and the securing of the two plates F, G of the middle section directly to the brackets H carried on said channel plate, I obtain a shorter and more rigid support for this section of the inner wall, and 50 at the same time eliminate the long plate which in the device of the aforesaid patent crosses the interior of the jamb and supports the middle section.

In order more clearly to explain the further 55 advantages of my present window-frame, I have shown in Figs. 3, 4 and 5 vertically sliding sashes disposed in the frame, the construction of said sashes, however, not being herein claimed. I is the upper 60 sash and J the lower sash. The lower member of sash J has a vertical downwardly projecting plate 41 which, when said sash is closed, as shown in Fig. 4, bears against the vertical face 4 of the sill. On the rear side 65 of said member is a plate 42 inwardly bent

and then turned downward, so that (also when said sash is closed) said down turned portion enters groove 6 in the sill. Hitherto where the lower sash has been constructed, as described, to coöperate with a rib on the 70 sill received between plates like 41 and 42, said rib projects above the level of the flat portion 1 of the sill, and so forms a dam preventing the escape of water lodging on said flat portion. But by placing the rib 75 below the level of the flat surface 1 of the sill, it is obvious that this dam is eliminated, and that there is always free drainage of the water over the rib and so to the outer inclined sill surface 2. 80

The upper sash I has an upwardly projecting plate 43 which enters between the upturned flanges 12, 14 of plates 11, 13, and on the sides of the sashes are plates 44, 45 which are received respectively in the slots 85 36 and 35. For the sake of clearness, I have omitted the suspension devices and counter-weights for the sashes.

Returning to the inner wall of the jamb, and particularly to the plates F, G of the 90 middle section thereof, it is to be noted that by reason of the horizontal slots in them, through which the attaching screws 37, 38, 39, 40 pass, each of these plates can be adjusted laterally by loosening the screws and 95 sliding the plate in one direction or the other. This enables me to make one part of either slot 35 or 36 tight, while leaving the remainder comparatively loose. For example, with the sashes closed, as shown 100 in Fig. 4, I may move the upper plate F to the right of the drawing, so more closely engaging the side plates 44 of the upper sash I in the upper part of their slot 36, and I may move the lower plate G to the 105 left of the drawing, so in like manner clamping the side plates 45 of the lower sash J in the lower part of their slot 35. But this movement of the two plates correspondingly increases the width so much of slot 110 36 as is below the upper sash, and so much of slot 35 as is above the lower sash. Consequently as either sash is moved to open the window, its side plates run more and more into the widened portions of the slots 115 and hence travel freely therein, so that although when closed the sashes are closely engaged, they are, nevertheless, easily opened.

In Figs. 4 and 5, I have shown packing 120 blocks 46 which, when the sashes are closed, bear against the ends of the meeting rails 47, 48. These blocks are bolted to the upper plates F of the middle section and their free lower ends extend over the joint 33 125 between said plates and the lower plates G, so that their presence offers no obstacle to the independent lateral adjustment of the said plates, as above described.

In order to adjust the initial width of the 130

slots 35, 36, the screws which secure the brackets H to the plates F and G pass through slots in said plates, and the screws 21 which attach section D to the brackets 5 20 and bar 19 also pass through slots in said section, so that by loosening these screws, said sections may be suitably moved with respect to one another, and the plates of the middle section with respect to section 10 E. The loops 27, 28 are given sufficient play within one another to permit of this movement of section D. The loops 15, 16 connecting the lintel plates 9 and 13 are also given sufficient play within one another 15 to enable the flanges 12, 14 on lintel plates 11 and 13 to be adjusted with respect to one another so as more or less tightly to engage sash plate 43.

I claim:

20 1. A metal window-frame, comprising a hollow jamb having its inner wall formed in three sections with vertical slots between them, the middle section being formed of two separated plates disposed vertically one 25 above the other and laterally adjustable each independently of the other.

2. A metal window-frame, comprising a hollow jamb, comprising a bent vertical plate integrally forming the rear wall, outer 30 wall and a portion of the front wall of said jamb, a channel plate having one arm united to said first-mentioned plate, the other arm forming a vertical section of the inner wall of said jamb, and the portion of said channel plate between said arms completing the 35

front wall of said jamb, a vertical section of said inner wall united to said rear wall, supports for said section, brackets on channel plate arm, and a middle vertical section of said inner wall interposed between 40 said sections and carried by said brackets; there being vertical slots between said sections.

3. A metal window-frame, as in claim 2, the said middle section being formed of two 45 plates disposed one above the other and independently adjustable laterally upon said brackets.

4. A metal window-frame, as in claim 2, the said vertical section being united to said 50 rear wall by mutually engaging loops and laterally adjustable upon said supports.

5. A metal window-frame, comprising a hollow jamb having its inner wall formed in three vertical sections with vertical slots between them, the middle section being formed of two separated plates disposed one above 55 the other, supports for said plates, the said plates being laterally and independently adjustable upon said supports, and a packing block 45 secured upon one of said plates and having its free end overlapping the joint between said plates.

In testimony whereof I have affixed my signature in presence of two witnesses.

IRVING H. ELLIOTT.
